ABSTRACT: This invention teaches a device incorporating in one very small area a very large number of "macromolecular" circuits. Each of these circuits includes a tunneling resistor in parallel with a small capacitor capable of controlled relaxation and both elements being in series with a further capacitor. This device at low temperatures serves as a memory element.

MACROMOLECULAR MEMORY CIRCUIT

THE INVENTION

This invention has been fabricated by assembling approximately one billion (10^9) separate circuits upon a chip having a length of 3 mm. and a width of 2 mm. Each of these circuits includes a tunneling resistor in parallel with a small capacitor capable of controlled relaxation and both of these elements as a unit being in series with a further capacitor. The operation of this device is dependent upon capacitors sufficiently small that a measurable voltage may be impressed thereon by the acquisition or loss of a single electronic charge (electron) which is roughly equal to 1.6×10^{-19} coulomb.

The structure and operation of this invention is best understood by reference to the drawings in which

FIG. 1 is a cross section of the structure upon which this invention is predicated;

FIG. 2 is a circuit diagram of one individual current path provided by this structure;

FIG. 3 is a graphical showing of charge variation in C_1 with applied voltage; and

FIG. 4 is a graphical showing of alternating current capacitance change at 100 kHz. as a function of applied voltage.

FIG. 1 depicts the structure assembled on a base which is a film of aluminum or tantalum having a noncritical thickness of about 2,000 Å. A thick oxide film is placed upon this base by exposure to gaseous or anodic oxidation. This film should be between 100 and 1,000 Å. thick. It is critical that this film be thick enough to inhibit tunneling. This thick oxide film is exposed to vaporous metal such as lead, tin, bismuth or indium under vacuum evaporation conditions to place upon the film a large number of discrete and separate metal droplets. These flattened droplets have an average diameter of about 100 Å.

The surfaces of these droplets remote from the thick oxide layer are now oxidized to form a thin tunneling barrier. This may be done by simple exposure to the atmosphere. This thin oxide layer has a thickness of about 10 Å. The preferred metals for these droplets are indium and tin. Bismuth and lead have also been used. A final thick metal film having a thickness of about 1,000 Å. was evaporated over the oxidized droplets to serve as an electrode. The other connection to the system is made through the 2,000 Å. thick base of aluminum or tantalum.

A consideration of any single metal drop with its associated oxide films and electrodes will show that each such drop and its associated parts produces in effect a macromolecular circuit as shown in FIG. 2. The thin oxide or tunneling film over the metal droplet forms the dielectric in capacitor C_R and the thick oxide film over the aluminum or tantalum base the dielectric of capacitor C_1 . The thin oxide film over each metal droplet serves as resistor R which passes current by the tunneling mechanism. The thick oxide layer over the aluminum or tantalum base must be thick enough to inhibit all tunneling. Capacitor C_R must be capable of relaxation in a reasonably short time.

This structure is to be distinguished from that reported by I. Giaever and H.R. Zeller: "Superconductivity of Small Tin Particles Measured by Tunneling," Physical Review Letters, Vol. 20, No. 26, June 24, 1968, pp. 1504-1507, in the inability of the thick oxide layer to permit tunneling.

If the device described above be cooled to the temperature of liquid helium (4.2° K.) and a small voltage V as shown in FIG. 2 applied, the charge upon capacitor C_1 will change in a series of discrete steps, with the ascent or descent from one charge level to the other representing the gain or loss of a single electron. This phenomenon has its basis in the fact that the charging of the capacitor C_1 is by tunneling through resistance R which is identical with the thin oxide layer of FIG. 1. This current is carried by individual electrons tunneling through this 10 Å. thick layer. If this charging process is carried out and the device permitted to warm up, the individual discrete steps shown in the solid lines of FIG. 3 tend to become less

distinct and the series of steps degenerates gradually into a smooth line. This represents the thermal agitation of the electrons in the metal.

This device may be used as a memory device by impressing upon it a small direct current voltage, and subsequently measuring the alternating current capacitance of the device after the host of capacitors C_R (FIG. 1) have been permitted to relax by the passage of time, or time assisted by the application of light flux if the components of the device be thin enough to permit the passage of light.

The necessity for this relaxation phenomenon will be appreciated if it is remembered that the charge on capacitor C_1 is capable of changing only in discrete units of electrostatic charge. The relaxation of capacitor C_R acts in effect as a voltage vernier and causes the voltage across the thin oxide layer to approach zero.

To employ this structure as a memory device, it is necessary to determine its alternating current capacitance as a function of the applied direct current voltage. This was done at a frequency of 100 kHz. by the techniques well known to the art and described fully in a publication entitled "Rectifying Semiconductor Contacts," H. K. Henisch, Oxford University Press, 1957, pp. 150-156.

25 The upper curve of FIG. 4 represents the ΔC (expressed in picofarads) of the entire assembly of the approximately 10^9 circuits when cooled to liquid helium temperature and in the absence of any previously applied voltage. Attention is invited to the very sharp dip in the capacitance curve at the zero voltage value of the abscissa. Intermediate the upper and lower curves of FIG. 4 is indicated two voltages V_{w1} and V_{w2} which are applied to the system from a square wave generator. This succession of two voltages V_{w1} and V_{w2} was applied for about 1 minute and at a frequency of 1 Hz. After relaxation was permitted to occur, the alternating current capacitive characteristics of the device were again measured with the results shown in the lower graph of FIG. 4. Note the precise coincidence of the sharp voltage dips of this curve with the values of the applied voltages.

2. The structure recited in claim 1 in which the final metal conductive film member is of light transmitting thinness for permitting light to flow through the film and upon the tin tunneling insulation layer.

3. The structure recited in claim 1 in which the metal droplets are deposited from a metal selected from the group consisting of tin, indium, bismuth and lead.

4. The structure recited in claim 1 in which the tunneling

layer is an oxide layer.

5. The structure recited in claim 1 in which the diameter of the metal droplets is about 100 Å.

6. The structure recited in claim 1 in which a rectangular area 3 mm. long and 2 mm. wide has a droplet population of approximately 10^9 .
